(57) **CLAIM**

We claim the ornamental design for an engine starter cord handle, as shown and described.

DESCRIPTION

FIG. 1 is a top perspective view of an engine starter cord handle according to the claimed design; FIG. 2 is a bottom perspective view of the claimed design of FIG. 1;

FIG. 3 is a front view of the claimed design of FIG. 1;

FIG. 4 is a rear view of the claimed design of FIG. 1;

FIG. 5 is a left side view of the claimed design of FIG. 1;

FIG. 6 is a right side view of the claimed design of FIG. 1;

FIG. 7 is a top view of the claimed design of FIG. 1;

FIG. 8 is a bottom view of the claimed design of FIG. 1; and,

FIG. 9 is a perspective of the claimed design of FIG. 1 shown in environmental use.
The broken lines shown represent unclaimed subject matter and form no part of the claimed design.

1 Claim, 7 Drawing Sheets
